HAIR WAVER

Filed May 29, 1930

UNITED STATES PATENT OFFICE

VICTOR VRYN, OF JERSEY CITY, NEW JERSEY, ASSIGNOR TO H. GOODMAN & SONS, INC., OF NEW YORK, N. Y., A CORPORATION

HAIR WAVER

Application filed May 29, 1930. Serial No. 456,876.

This invention relates to improvements in hair wavers of the type having a movable comb associated with a stationary comb and intended for use primarily by women in waving their own hair.

The object of the present invention is to provide a hair waver comprising a pair of combs in fixed parallel relation in conjunction with a third comb shiftable lengthwise between the pair of fixed combs whereby a wave may be produced which will very closely simulate the appearance of naturally wavy hair.

To produce such a wave it is necessary to undulate the hair in two planes relatively to the scalp, that is to say the hair must be waved both vertically and horizontally.

In the patent application of Abraham and Jacob Goodman, Serial No. 357,921, filed April 22, 1929, there is disclosed a hair waving device of this type having means for producing a vertical ridge in the hair but said device has only a single stationary comb and does not operate satisfactorily to form the required lateral or horizontal wave.

I have found that in order to produce such a wave effectively the hair must be loosely held between the teeth of two substantially parallel fixed combs so that the hair will be engaged at two spaced opposite points but will be free to move in between said points upon shifting the movable comb.

In the accompanying drawings illustrating one form of the invention,

Figure 1 is a side elevation of the hair waver showing, in dotted lines, the movable comb in shifted position. In this view, for the sake of clarity, the teeth of the movable comb are not shown except by the dotted lines.

Fig. 2 is a bottom plan view of the device showing the parts in the position indicated by the dotted lines in Fig. 1.

Fig. 3 is a top plan view of the same.

Fig. 4 is a sectional view on the line 4—4 of Fig. 3,

Fig. 5 is an end elevation and,

Figs. 6 and 7 are diagrammatic views indicating the manner of operation in producing the lateral or horizontal wave.

The hair waver, in the embodiment illustrated in the drawings, comprises a member 10 which is arched lengthwise to conform to the general curvature of the scalp and has downwardly extending parallel sides 11. 55 This structure may be made by stamping it from a single piece of metal, preferably aluminum because of its lightness and non-rusting properties. To further decrease the weight and to provide for circulation of air 60 through the device, openings 12 may be formed in the said member.

A pair of combs 13 are fixed to the member 10. These combs may be formed integral with the side members 11 but I prefer to make them each of a separate piece of celluloid, rubber or the like, attached to the inner face of the side 11 by eyelet rivets 14.

The combs are curved similarly to the curvature of the member 10 and their teeth are 70 preferably inclined, as shown in Fig. 1, so as to give a better hold in the hair: the teeth of the two combs 13 extending in the same direction and being parallel to each other.

A slide 15 is mounted on the member 10 75 to slide in the longitudinal slots 16 formed therein. The slide is preferably made of a piece of metal formed with shoulders 17 which bear against the inner surface of the member 10, and with lugs 18 which are bent 80 down upon the outer surface of said member. A handle or knob 19 is provided for conveniently moving the slide. A single comb 20, similar to the combs 13 but with its teeth preferably inclined in the opposite 85 direction, is fixed to the slide 15 by means of eyelet rivets 21.

A curved tongue or bar 22 is hinged at 23 to an extension 24 at one end of one of the sides 11 of the member 10. A catch 25, 90 for holding the tongue in its closed position indicated by the dotted lines in Fig. 1 is formed on the extension 26 at the opposite end of said side.

It will be seen as clearly appears from 95 Figs. 2 and 4, that the shifting comb 20 is positioned somewhat closer to one of the pair of fixed combs 13 than to the other, and that the tongue extends substantially midway between the comb 20 and said adja- 100

cent comb 13, and, in its closed position, lies in a plane above the root of the teeth of the combs.

In use the device is engaged in the hair with the side that carries the tongue positioned towards the roots of the hair and it is then secured in place by locking the free end of the tongue in the catch. This raises the hair from the scalp and forms a ridge or vertical undulation therein. The movable comb 20, which in its initial position lies opposite the fixed combs 13 as indicated diagrammatically in Fig. 6, is then shifted lengthwise to the position shown by the dotted lines in Fig. 1, thereby shifting the hair laterally in between the pair of fixed combs as illustrated in Fig. 7, and thus producing the desired lateral or horizontal wave without tearing or applying any tension on the hair. Wetting or dampening the hair prior to or after insertion of the device facilitates the formation of the waves. The combs are now permitted to remain in the hair until the waves have been formed and set, after which the tongue is unfastened and the device removed from the hair.

The extent of the shifting movement of the movable comb 20, in relation to the pair of relatively stationary combs 13, determines the length of the wave which may be varied as desired. The construction of my device is such that a long sweeping wave, closely simulating a natural wave, may be readily produced. The opposite inclination of the teeth of the comb 20 with respect to those of the combs 13 gives a firm bite on the hair and not only assists in holding the device in place in the hair but is also conducive to forming the desired wave.

If desired the device may be made in the form of "rights" and "lefts" for use, respectively, on the right or left side of the part of the hair. The devices so formed differ from each other mainly in that in one case the tongue is hinged to one side of the supporting member 10 while in the other case it is hinged to the opposite side. Furthermore, a plurality of the devices may be used at one time so as to form a number of waves simultaneously.

It will be understood that modifications may be made in the construction and arrangement of parts herein illustrated and described within the scope of the invention pointed out in the claims.

What I claim is:—

1. A hair waver comprising a supporting member, a pair of combs having downwardly extending teeth fixed in substantially parallel relation on opposite sides of said member, a third comb having downwardly extending teeth slidable on said member between the pair of fixed combs for shifting movement lengthwise relatively thereto, a tongue hinged to said member at one end

and extending in its closed position between the movable comb and one of the fixed combs, and a catch on the supporting member for lockingly engaging the free end of the tongue in closed position.

2. A hair waver comprising a supporting member having downwardly extending parallel side portions, a pair of combs one fixed to each side portion, a slide mounted to slide lengthwise in longitudinal slots formed in the supporting member between and parallel to its side portions, a single comb fixed to said slide, a tongue hinged to the supporting member at an end of one of its side portions, and a catch at the opposite end of said side portion for lockingly engaging the tongue in closed position.

3. A hair waver comprising a supporting member having downwardly extending parallel side portions, a pair of combs fixed one to each side portions, said combs having parallel inclined teeth, a slide mounted to slide lengthwise in longitudinal slots formed in the supporting member between and parallel to its side portions, a single comb fixed to said slide and having its teeth inclined in the opposite direction to those of the pair of combs, said single comb being disposed somewhat closer to one of the pair of combs than to the other, a tongue hinged at one end to one of the side portions of the supporting member and extending in closed position lengthwise between the single comb and the closer one of the pair of combs and lying in a plane above the roots of the teeth of said combs, and a catch at the opposite end of said side portion for lockingly engaging the tongue.

Signed at New York city in the county of New York and State of New York this 26th day of May A. D. 1930.

VICTOR VRYN.
